(57) CLAIM

The ornamental design for a cosmetic jar, as shown and described.

DESCRIPTION

FIG. 1 is a top perspective view of a cosmetic jar, showing my new design;

FIG. 2 is an exploded top perspective view thereof;

FIG. 3 is a side view thereof;

FIG. 4 is an opposite side view thereof;

FIG. 5 is a right side view thereof;

FIG. 6 is a top view thereof; and,

FIG. 7 is a bottom view thereof.

The broken lines in the figures illustrate the portions of the cosmetic jar and form no part of the claimed design.
